UNITED STATES PATENT OFFICE

EDGAR A. TERRELL, OF CHARLOTTE, NORTH CAROLINA

BOBBIN STRIPPER

Application filed November 14, 1923. Serial No. 319,284.

The invention has relation to machines of the class used in the textile industry for the purpose of stripping so-called feeler-waste, i. e., residues of weft or filling, from bobbins that have been expelled from the working shuttle of an automatic weft-replenishing loom in bobbin-changing operations brought about under the control of a so-called weft or filling-feeler. More particularly, it relates to bobbin-stripping machines of the type having blades or the like by which the bunch of weft or filling remaining on an expelled bobbin is removed from the bobbin-barrel by a scraping action taking place lengthwise along the bobbin-barrel.

The invention comprises improvements in connection with the inclined guide-way or chute along which bobbins requiring to be stripped pass on their way from a supply-hopper to the stripping devices; also, in connection with the stripper-elements whereby the residue of filling remaining upon a bobbin is stripped from the bobbin-barrel lengthwise of the latter; also, in connection with the means for preventing a bobbin that is fed into position to be acted upon by the stripper-blades from becoming displaced longitudinally; and improvements in connection with the jaw-members of the reciprocating gripper by which a bobbin is drawn lengthwise through the stripper-elements-assemblage in the stripping operation.

The accompanying drawings illustrate the features of the invention applied in a bobbin-stripping machine of the type aforesaid embodying certain of the principles of the machine of U. S. Letters Patent for quill cleaning machine, No. 1,235,399, granted July 31, 1917 upon application of George W. Utsman; and of U. S. Letters Patent for machine for cleaning bobbins, No. 1,273,075, granted July 16, 1918 upon application of Walter W. Linder.

In the drawings,—

Fig. 1 is a view of the said machine in side elevation, with the bobbin guideway or chute omitted, these being shown separately in Figs. 3, 4, 5, 6.

Fig. 2 is a plan view of the parts which are shown in Fig. 1.

Fig. 3 is a side view of the bobbin guideway or chute, looking in the same direction as in Fig. 1.

Fig. 4 is a side view thereof looking in the opposite direction.

Fig. 5 is a view thereof looking from the left-hand side of Fig. 3.

Fig. 6 is a view in section in the plane of line 6, 6, Fig. 4.

Fig. 7 is a partly sectional view, on a larger scale than the preceding views, showing the so-called shutter and its normal position with relation to the position of a bobbin which has dropped in between the sets of stripper-blades (not shown).

Fig. 8 is a view looking from the right in Fig. 7.

Fig. 9 is a partly sectional view showing certain portions of the stripper-blade mechanism which are located at the top in Fig. 2, 70 namely at the machine-side opposite that shown in Fig. 1.

Fig. 10 is an isometric view of one of the bobbin-rests adjacent the acting ends of the stripper-blades.

Fig. 11 is a plan view of the so-called cross-head, the gripper-jaws carried thereby, and certain associated parts, with portions of the cross-head guides broken away.

Fig. 12 is a partly sectional view of one of the gripper-jaws and its adjuncts.

Fig. 13 is an isometric view of the gripper-jaw closing spring and the castellated spring drum.

Fig. 14 shows the locking pin for the spring drum, and the nut of said pin.

Fig. 15 shows one of the eccentric gripper-jaw-studs.

Fig. 16 shows one of the locking pins for the eccentric gripper-jaw-studs.

The machine shown in the drawings has a frame constructed with a bed 1 comprising two side-members, indicated in Fig. 2, in spaced apart, parallel relation, supported upon legs 2, 2. Above this bed is disposed in practice a bobbin-chute which serves to receive bobbins which are supplied to the machine for the purpose of being operated upon, and to conduct them toward the stripping point in the machine. The chute is omitted

55

65

75

90

95

100

from the machine in Figs. 1 and 2, in order that parts located below it in the machine may be shown. It is shown separately in Figs. 3, 4, 5, 6. In practice the chute is so contrived and so disposed in the machine that a bobbin placed therein will be conducted to the stripping point, and after having been given a position extending lengthwise in a horizontal position lengthwise of the machine is deposited between the two sets of stripper-blades, 45, 45, with the rings on its head resting upon bobbin-rests 47, 47, and the portion of the bobbin next adjoining such head in position to be acted upon by the stripper-blades. In this position of the bobbin its head is presented in readiness for being grasped by the traveling gripper-jaws 29, 30, which are employed for pulling the bobbin lengthwise through between the stripper-blades for the performance of the stripping operation.

The said gripper-jaws are carried by the cross-head 4. Such cross-head is mounted for horizontal movement in guides 21, 21, in connection with the side-members aforesaid of the bed 1. This cross-head 4 is coupled by a longitudinally adjustable connecting-rod 20 with a slotted link 3, within the slot of which works the crank-pin 37 of a crank 6 on the cross-shaft 35 of the machine, to transform the rotary motion of said shaft into a reciprocating motion which will alternately advance the slide and its gripping jaws 29, 30, to the stripping blades and carry them away therefrom. A bearing-rod 201 extending from the rear side of link 3 works in a bearing at 59 on the bed, to support the other end of the reciprocating unit.

The bobbin-chute shown separately in Figs. 3, 4, 5, 6, and comprising the horizontal portion 50 in which the bobbins are deposited, and along which they are pushed by hand, and the inclined arc-shaped portion 51 down which the bobbins slide under the influence of gravity, is composed mainly of two cheek-plates 52, 52, and two chute-castings 119, 120, to which said cheek-plates are bolted, the said chute-castings serving as feet for the bobbin-chute and being attached by bolts 53, 53, to the surfaces 54, 54, Figs. 1 and 2, of the bed 1. The chute-rails 139, 139, attached to the upper edges of the cheek-plates 52, 52, at the inner faces of the latter, are spaced apart just sufficiently to permit the barrel of a bobbin to enter between them, but not sufficiently to admit the bobbin-head, so that a bobbin dropped into the bobbin-chute will be supported by its head, or by the metal rings which customarily surround said head as in Figs. 8 and 11, resting upon the two chute-rails with its barrel hanging down within the chute. As the bobbin moves along the chute toward the delivery end thereof the bobbin-head or the said rings will slide along the chute-rails. Within 65 the bobbin-chute are located bobbin guide-

strips 129, 130, spaced apart just sufficiently to admit between them the small part of a bobbin-barrel near its tip. These guide-strips determine the position of the bobbin-tip and barrel transversely, and prevent it from assuming a position inclined to one side or the other. They also serve to hold the barrels of successive bobbins in line with one another, and prevent one from lapping past another.

As one feature of the invention I provide for adjustment of the said bobbin-guide-strips transversely. Thus the said guide-strips are furnished with pins or studs 133, 133, projecting transversely outward from the outer sides of the guide-strips. The said pins or studs occupy holes in the cheek-plates, in the chute-castings, and in nipples in connection with the chute-castings, as shown in Figs. 5 and 6. Thereby the guide-strips are supported. The pins or studs are capable of being moved lengthwise within the holes occupied by them, as may be required in adjusting the guide-strips transversely with relation to each other, or it might be with relation to the cheek-plates. The adjustments are retained by means of clamping screws 1331, 1331, applied to the said nipples and engaging by their inner ends with the said pins or studs.

As another feature of invention I employ in connection with the inclined arc-shaped portion 51 of the bobbin-chute one or more pairs of bobbin-trip-pins 128, 128, located just below the guide-strips 129, 130, in the path of the tip of a bobbin descending such portion 51 of the bobbin-chute, and arranged so that the two pins of a pair project inwardly toward each other from the two cheek-plates, but with a clear space or interval between their tips. Such space or interval is shown in Fig. 6. The trip-pins serve as detents to check the advance of the bobbin-tip while the bobbin-head continues its progress; in other words, the trip-pins are employed for overturning the bobbin so that it lies substantially horizontal as it arrives at the foot of the arc-shaped portion 51 of the bobbin-chute. The said tips of the two strip-pins of a pair are intended to be located sufficiently close to each other to prevent a bobbin tip from passing between them, but are separated by an intervening space sufficient to permit a length of yarn trailing from the bobbin to slip through. This provision for permitting pendant yarn to go through avoids the clogging of the delivery portion of the bobbin-chute with loose yarns. It obviates likelihood of a bobbin tip remaining hung up in said portion of the chute, as in consequence of two or more bobbins being connected together by loose yarn; it guards against a bobbin entering between the stripper-blades with its tip held too high and the bobbin consequently in a longitudinally inclined position. Two pairs of trip-

pins are employed in the illustrated machine. To provide for varying the setting of the two trip-pins of a pair with relation to each other, so as to vary the extent of separation of their proximate ends, the stems of the said pins are screw-threaded and occupy screw-threaded holes in the chute-castings 119, 120. By turning the trip-pins in the said holes they are shifted endwise to locate their proximate ends at the required distance apart. The pins are secured by means of lock-nuts 1281, 1281, against accidental loss of adjustment. By providing trip-pin receiving holes 1282, 1282, in the cheek-plates and chute-castings, at different distances from the chute-rails 139, 139, it is made possible to shift the trip-pins from one set of holes to another to suit different lengths of bobbins operated upon.

At 134 is a rest-pin at the lower end of the inclined arc-like portion of the bobbin-chute, upon which the tip of a bobbin takes bearing as the bobbin arrives at said lower end. Said rest-pin serves to assure that the bobbin shall assume a horizontally extended position, and it sustains the bobbin-tip until the bobbin is drawn from it by the action of the traveling gripper-jaws.

A segmental guard 136 overlying the inclined arc-like portion 51 of the bobbin-chute, and paralleling such portion, prevents the head-ends of bobbins descending such portion from projecting too far outward from the bobbin-chute, and thereby provides against outward displacement of a bobbin. This guard cooperates with the chute-rails 139, 139, in delivering the bobbin between the opposing sets of stripper-blades 45, 45, with the bobbin-head resting upon the rests 47, 47, and with the portion of the bobbin that immediately adjoins its head presented properly to the acting ends of the stripper-blades. The said guard is carried by brackets 131, 131, which are held to the chute-casting 120 by means of bolts 1311, 1311. To enable the guard to be adjusted inwardly or outwardly as may be required in practice, the brackets are formed with elongated slots 1312, 1312.

The arc-shaped portion of the bobbin-chute is formed as a quadrant constituted in effect by a development of the periphery of a cone corresponding substantially with a bobbin, so that the portion of a bobbin which contacts with the chute-rails 139, 139, may roll upon the arc-shaped portions of the said chute-rails without material departure from substantially true radial position, while changing from vertically erect to horizontal position, subject of course to the detaining effect of the bobbin trip-pins upon the tip of the bobbin.

Having reference now to the stripper-blades and the means and manner of actuating the same:—

As has been indicated already, there are employed in the present instance two sets of stripper-blades 45, 45, one of such sets opposing the other, as indicated in Figs. 2 and 9. The stripper-blades are mounted to move lengthwise, transversely of the machine, in guideways in connection with the bed 1, the said guideways being separated by ribs 451, 451, and the blades being held down in the respective guideways by cover-plates 46, 46. In the present instance each set of stripper-blades comprises a thin blade arranged to act by its concaved chisel-like inner end against a bobbin close to the shoulder of the bobbin-head resting upon the bobbin-rests 47, 47, and a second stripper-blade having a broader and serrated concaved working end.

For the actuation of the stripper-blades, their outer ends are connected pivotally with upstanding arms of stripper-levers 168, 169, Figs. 1, 2, and 9, which are sleeved loosely upon rock-shafts 179, 179, at the opposite sides of the machine. In the case of each rockshaft 179, an arm 166 sleeved upon such rockshaft and made fast thereto by clamping screws extends down from the shaft at the outer side of a downwardly extending arm of the lever 169. A stud 40 extending through holes in the two arms has a head which makes contact with the outer side of the arm 166. The stem of the said stud at the inner side of the downwardly extending arm of stripper-lever 169 has mounted thereon an expanding spiral spring 41 which is confined between the said arm of stripper-lever 169 and the washer and nut 42 upon the screw-threaded inner extremity of the stud. As will be obvious, when the rockshaft 179 is turned in a clockwise direction as indicated by the arrow in Fig. 9, movement will be imparted through the described connections to the stripper-lever 169 in the direction to slide the connected stripper-blade 45 inward, the spring 41 yielding compressively as soon as the working end of the said stripper-blade brings up firmly against the bobbin, so as through such yielding to obviate injury to the parts or to the bobbin. An arm 171 sleeved upon each rockshaft 179 and made fast thereto by clamping screws, as shown in Figs. 1 and 9, and extending upward from the rockshaft at the inner side of a lug 1681 projecting rearward from the stripper-lever 168, has combined therewith a stud 40 extending through the said lug and the arm 171, with its head at the outer side of the lug, and with an expanding spiral spring 41 mounted upon the stem of the stud between the inner side of the arm 171 and a nut and washer 42 upon the threaded inner end of the stud. As will be obvious, the aforesaid turning movement of the rockshaft in clockwise direction as indicated by the arrow in Fig. 9, will cause the arm 171 to act compressively against the spring 41 to actuate the stripper-lever 168 to

move the associated stripper-blade 45 inward, with capacity to yield as soon as the working end of the said blade brings up solidly against a bobbin. When the rockshaft is rocked ⁵ reversely, the arms 166 and 171 will act positively upon the stripper-levers 169 and 168 to move the said levers to withdraw the stripper-blades outwardly.

As will be understood, the two rockshafts ¹⁰ 179, 179, located at the opposite sides of the bed 1, will be rocked simultaneously, but oppositely with reference to each other, in order that the opposing sets of stripper-blades may be caused to move simultaneously toward ¹⁵ each other, for engagement with a bobbin at opposite sides of the latter prior to the withdrawal of the bobbin lengthwise from between the stripper-blades, and that following the stripping operation they may be caused ²⁰ to move simultaneously outwardly away from each other. The rockshafts 179, 179, are provided with arms 31, 31, engaging with cams 16, 16, on the shaft 35 so that through the rotation of the said shaft and cams the rock- ²⁵ shafts are rocked as has been indicated.

A shutter 36 by means of which a bobbin descending the arc-shaped portion 51 of the bobbin-chute is prevented from longitudinal displacement, large-end first, as it lands upon ³⁰ the bobbin-rests 47, 47, and until it becomes grasped between the working ends of the opposing sets of stripper-blades, is shown in its working relations in Figs. 1 and 2, and separately in Figs. 7 and 8. It is mounted piv- ³⁵ otally at 361 upon a fixed support, and is adapted to swing around the pivot in a vertical plane closely adjacent the bobbin-rests. The shutter is shown in upraised position in Figs. 7 and 8 to afford opportunity for the ⁴⁰ gripper-jaws 29 and 30 of the cross-head 4 to engage with the bobbin-head at opposite sides transversely of the said head. In the said position of the shutter 36, it is properly located with reference to the bobbin occupying ⁴⁵ the feed-chute above and resting upon the bobbin in stripping position so that, as the latter bobbin is being withdrawn by the bobbin-pulling movement of the gripper-jaws, the shutter prevents any movement of ⁵⁰ the upper bobbin in the same direction.

For the actuation of the shutter a pull-rod ³⁶², Figs. 7 and 8, is employed intermediate ⁵⁵ an arm 363 of the adjacent rockshaft 179, and an arm of the shutter extending outward from the pivot 361 thereof. The pull-rod 362 is engaged with the said arm of the shutter by means of an engaging piece 364 that is fixed by means of a clamping screw 365 upon ⁶⁰ the upper portion of the said pull-rod at the required height. This engaging piece 364 works in a slot 366 in the arm aforesaid of the shutter. When arm 363 swings upward, the freedom of the engaging piece 364 to move ⁶⁵ upward in the slot 366 leaves the shutter free to descend under the influence of gravity to-

ward a position alongside the bobbin-rests. Hence, in case the shutter lands on top of a bobbin-head projecting under the shutter, no breakage will result. When the arm swings downward the engaging piece 364 moves ⁷⁰ downward within the slot 366 until it encounters the bottom of the slot 366 before movement is imparted to the shutter 36. This permits a dwell of the shutter in its lower position to afford opportunity for a bobbin ⁷⁵ to descend completely into contact with the bobbin-rests 47. During the remainder of the swinging movement of the arm 363, it transmits lifting movement to the shutter 36.

On account of the wear due to contact of ⁸⁰ the bobbin-head rings with the bobbin-rests 47, 47, and to movement of the said rings across the said bobbin-rests as the bobbins are withdrawn by the action of the gripper-jaws, I employ removably applied rests constituted ⁸⁵ by blocks shaped as shown in Figs. 9 and 10, secured in place upon the supports therefor by means of screws 471. I form these rest pieces 47, 47, of material capable of effectively ⁹⁰ withstanding the wear.

To enable the extent of the movement of the respective stripper-blades inward to be regulated, so as to avoid likelihood of injury to the working ends of the stripper-blades through too severe an impact against a bobbin about to be stripped, I provide an adjustment screw 43, Fig. 1, in connection with each arm 166 and each lug 1681. The screw 43 that is applied to an arm 166 extends inwardly therefrom toward the adjacent downwardly extending arm of the associated stripper-lever 169, so as through engagement between the said downwardly extending arm and the inner end of the adjustment screw, the angular position which the stripper- ¹⁰⁵ lever 169 is caused to assume upon the rock- shaft 179 through the action of the corresponding spring 41 is determined. In like manner, the adjustment screw 43 that is applied to the lug 1681 of the stripper-lever 168 ¹¹⁰ extends inward toward the adjacent upstanding arm 171 on rockshaft 179 so that, through engagement between the inner end of the said adjustment screw and the said upstanding arm, the angular position that the stripper- ¹¹⁵ lever 168 is caused to assume upon the rock- shaft under the action of the corresponding spring 41 is determined.

The broad-ended stripper-blades 45, 45 are arranged so that as they move inward toward each other and a bobbin interposed between them their comparatively broad ends close against the exterior of any bunch of weft or filling, or other windings, remaining upon the bobbin. In the stripping action ¹²⁰ which ensues as the bobbin is drawn endwise between the opposing sets of stripper-blades by the traveling gripper-jaws, the said broad-ended jaws keep hold of said bunch or other winding and wipe it toward the tip of the ¹²⁵ 130

5 bobbin. The chisel-ended stripper-blades penetrate between the shoulder of the bobbin-head and any bunch or other windings, and cooperate with the broad-ended blades in holding back the waste as the bobbin is withdrawn, in addition to stripping from the bobbin any turns or coils of filling that may not have accompanied the main residual collection as the latter is removed by the 10 broad-ended blades. Inasmuch as all four of the stripper-blades are actuated as described hereinabove to press yieldingly against the bobbin with a firm contact therewith, the stripping action is complete and uniform in 15 dealing with bobbins having residual bunches or windings of varying quantity, tightness of wind, &c.

As has been stated, the gripper-jaws 29, 30, are carried by the traveling cross-head 4. 20 By the reciprocating movements of the said carriage the jaws (being at such time open) are moved toward the position occupied by the head of a bobbin supplied through the arc-shaped delivery portion of the bobbin-25 chute. They are caused to close upon and grasp the bobbin-head. They then are moved away from such position, pulling such bobbin endwise between the stripper-blades. They then are opened to release the stripped 30 bobbin, and are latched in open condition, to remain open until they have again reached the position for taking hold of a bobbin presented to be stripped.

The gripper-jaws 29, 30, are constituted by 35 levers that are mounted by means of pivotal screws 27, 27, (see more particularly Fig. 11), upon the traveling cross-head 4, to swing in a horizontal plane so as to cause their grasping ends to approach and recede from 40 each other transversely. The said grasping ends are constructed properly for engagement with the head of a bobbin. In this instance they are grooved vertically, to receive the rings which are applied to the heads of 45 bobbins employed in looms in which weft replenishment is effected automatically through change of bobbins in the working shuttle.

According to the present invention the gripper-jaws 29, 30, are actuated in their 50 closing as well as in their opening by means of a cam 23, mounted upon cross-head 4, having a pivot constituted by a vertical post or stud 232 carried by the cross-head around which the cam is capable of swinging in a 55 horizontal plane, and having cam-slots 231, 231, into which enter cam-followers 26, 26, carried by the gripper-jaws. For the purpose of actuating the slotted cam 23 automatically to occasion the closing of the jaws together 60 at the required times, a spring-drum 34 surrounded by a helical torsion spring 32 is placed upon the post 232 above the slotted cam, with one end of the spring engaged with a projection on the slotted cam, and 65 with the spring drum locked against angular

movement around said post by means of a pin 59 (shown separately in Fig. 14) occupying a diametrical hole in the post, and having a projecting end thereof entered into one of the notches of the castellated top of the drum.

The bent inner end of the pin prevents such end from passing in one direction through the hole in the post, while a nut 591, Fig. 14, applied externally of the castellations of the drum to a screw-threaded portion of the pin prevents the pin from shifting endwise in the opposite direction. The spring acts with a 70 tendency to swing the slotted cam in the direction to close the gripping jaws toward each other. The tension of the spring may be 75 regulated by removing the pin 59, turning the spring drum in the proper direction to secure the desired tension, and replacing the pin. For the purpose of actuating the slotted

cam to separate the gripper-jaws as the outgoing movement of the cross-head is completed, (that is to say, the movement away from the bobbin-chute and stripper-blades,) a stationary stop 91, constituted by a roll, is 80 positioned where it will be encountered by an

outstanding arm of the slotted cam toward the end of the said outgoing movement. Thereby the slotted cam is swung around the post 232, and the cam-slots occasion the required 85 opening of the gripper-jaws. The 90 jaws are retained in open condition through the engagement of a shoulder 233 on the slotted cam by a latch 24, pivoted at 25 upon

the cross-head and actuated by means of a spring 28 to effect such engagement. The 95 gripper-jaws, remaining open during the movement of the cross-head toward the bobbin-chute and stripper-blades, and until the engaging portions of the jaws have been disposed at opposite sides of a bobbin-head resting upon the bobbin-rests 47, 47, are caused to close upon such bobbin-head through turning movement of the slotted cam due to the action of spring 32, in consequence of disengagement of latch 24 through being carried 100 against a stationary stop 81. The said stop is constituted by a screw, so that its acting portion may be shifted endwise to render it 105 possible to cause the closing of the jaws to occur at the right point in the ingoing movement of the cross-head for bringing about proper engagement of the jaws with the bobbin-head. During the outgoing movement 110 of the cross-head, the jaws are caused by the tension of spring 32 to remain closed upon the bobbin-head, so that they pull the bobbin through between the stripper-blades and carry it along until the outstanding portion 115 of the slotted cam encounters the stationary stop 91 and is turned through engagement therewith to open the jaws. As they open, the jaws release the stripped bobbin, permitting it to drop. The latch 24 again latches the slotted cam in position to hold the gripper- 120

125

130

135

140

145

150

jaws open as required for the ensuing inbound travel of the cross-head.

A feature of the invention consists in provisions for rendering the gripper-jaws individually adjustable transversely. In virtue of this adjustability it is rendered possible to ensure that in closing upon the head of a bobbin lying between the opposing sets of stripper-blades the two gripper-jaws shall bear with equal pressure and force against the opposite sides of the bobbin-head, without tendency to bear the bobbin over bodily toward one side or the other. In the present instance I secure the said adjustability through employing as cam-followers 26, 26, pins having, as shown in Figs. 11, 12, and 15, cylindrical base-portions which occupy cylindrical holes in the gripper-jaw members, and further having cylindrical upper portions which are located upon said base-portions eccentrically with relation to the axes of the base-portions. These eccentrically-disposed upper-portions enter the cam-slots 231, 231. Inasmuch as the eccentrically-related upper-portions of the cam-followers work within and have to follow the cam-slots 231, 231, in the slotted cam 23, it will be seen that angular (rotative) adjustment of the cam-followers about their own axes will bring about modification of the positions taken by the acting ends of the gripper-jaws as the said ends are closed together by the action of the slotted cam. For the purpose of enabling such angular adjustment of the cam-followers about their individual axes to be effected, a screw-driver slot or nick is made in the exposed end of each cam-follower. For the purpose of enabling the respective cam-followers to be locked in the positions given them in their angular adjustments, a horizontal hole is formed in each gripper-jaw member and in such hole is placed a pin 261, Figs. 12 and 16, having in an intermediate portion of its length a concavity 262, Fig. 16, into which the base-portion of the corresponding cam-follower fits. The projecting end of the said pin 261 is threaded and has applied thereto a locknut 263. When this locknut is loosened, the locking pin 261 is sufficiently loose in its engagement with the base-portion of the cam-follower, and this permits any desired angular (rotary) adjustment of the cam-follower. When the locknut is tightened up against the outer side of the jaw-member the pin 261 is drawn endwise outwardly, so that one side of the concavity in such pin is forced firmly into engagement with the base-portion of the cam-follower. To give an effective hold, the said base-portion is roughened, as by knurling, as shown. To provide for varying the point in the outgoing stroke of the cross-head at which the gripper-jaws shall be opened to release the stripped bobbin held thereby and permit such bobbin to drop, stop 91 is made adjustable longitudinally of the machine. To this end,

in the present instance the stand 9 in which stop 91 is mounted by means of a pivotal screw 92, Fig. 11, has formed in its foot 93 a slot 94 for the bolt 95 by which such stand is fixed in place.

For the purpose of removing from the barrel of a bobbin which is being cleaned any coils or turns of yarn which may remain upon the said barrel following the action of the two sets of stripper-blades, I employ one or a pair of clearers or wipers 123, 123, shown best in Fig. 2. The said clearers or wipers are actuated with a timing independent of that of the stripper-blades, to open and close with relation to the path along which a bobbin is transported by the grippers in being drawn from between the stripper-blades. In this instance, I employ a pair of the said clearers or wipers, constituted of a pair of arms equipped with pieces of material suitable for clearer or wiper action, such as felt, leather, or the like. The arms, respectively, are mounted upon vertical pivots 127, 127, which are located at opposite sides of the path in which the gripper-jaws are reciprocated. The arms are capable of swinging transversely toward and from each other around these pivots. The bobbin-engaging extremities of the clearers or wipers are located just back of the stripper-blades. For the purpose of spreading them apart so as to permit access of the grippers to the head of a bobbin occupying a position between the two sets of stripper-blades, I utilize the movement of the gripper-carriage toward the stripper-blades. For causing them to close against opposite sides of the bobbin-barrel after the grippers have been withdrawn sufficiently to carry the bobbin-head beyond their acting extremities, the arms are urged toward each other by means of spiral springs 164, 164, which tend to close the strippers or wipers together. Such springs in the present instance are confined between the arms and posts 126, 126, that are fixedly connected with the supporting frame at the outer sides of the arms, so that the springs act expansively against the arms. The normal inward positions of the arms, and the closeness of the approach of their extremities are determined by means of contact-screws 128, 128, carried by outwardly-extending projections of the arms and arranged to make contact by their inner ends with outer surfaces of upstanding fixed portions of bed 1. The working positions, and the relations, of the parts are such that in the stroke of the gripper-jaw carriage toward the stripper-blades from the position in which it is represented in Figs. 1 and 2, the leading portions of the gripper-jaws act against curved inner surfaces of the arms 123, 123, to press outwardly the bobbin-engaging extremities of said arms. Thereby the said extremities are spaced apart sufficiently to permit the bobbin-engaging ends

of the gripper-jaws to pass onward between them far enough to grasp the head of a bobbin lying between the two sets of stripper-blades, and to permit the bobbin-head to pass between them in the return movement of the carriage toward the position shown in Fig. 1. By the concluding portion of the said stroke toward the stripper-blades the wide-open jaws are projected beyond the bobbin-engaging extremities of the clearer or wiper-arms 123, 123, sufficiently to embrace and close upon the head of a bobbin that has been dropped between the two sets of stripper-blades. In the return movement of the carriage, as soon as the bobbin-head has been carried past the acting extremities of the clearers or wipers, the said acting extremities are caused by the springs 164, 164, to take bearing against the bobbin at opposite sides thereof, so as to act thereupon for wiping and clearing purposes. Following the complete withdrawal of the bobbin-tip from between the clearers or wipers, the latter swing toward each other until arrested in the predetermined closeness of approach by the stop-screws 128, 128. Through adjustment of the said stop-screws, the closeness of approach of the clearers or wipers to each other may be regulated.

30 What is claimed as the invention is:—

1. In a bobbin-stripper machine, the combination with stripper-devices, and a reciprocating device for moving a bobbin relative to said devices to effect stripping, of a bobbin-guiding chute by which a bobbin to be stripped is delivered to the stripper-devices, said chute controlling the bobbin by the bobbin-head, bobbin-guide strips in connection with the chute between which the bobbin-barrel is guided, said strips transversely adjustable, supporting pins or studs combined with said strips, and means engaging with such pins or studs to hold the strips in adjusted position.

45 2. In a bobbin-stripper machine, the combination with stripper-devices, and an inclined bobbin-chute in which a bobbin hangs suspended by its head as it progresses toward the stripper-devices, of a pair of bobbin trip-pins in connection with said chute having the proximate ends of the pins separated by a space for the passage of trailing yarn.

50 3. In a bobbin-stripper machine, the combination with stripper-devices, and an inclined bobbin-chute in which a bobbin hangs suspended by its head as it progresses toward the stripper-devices, of a pair of bobbin trip-pins in connection with said chute having the proximate ends thereof separated by a space for the passage of trailing yarn, and means for adjustment of the said bobbin trip-pins to vary the dimensions of such space.

55 4. In a bobbin-stripper machine, the combination with stripper-devices and an inclined bobbin-chute in which a bobbin hangs

suspended by its head as it progresses toward the stripper-devices, of a pair of bobbin trip-pins in connection with said chute having the proximate ends thereof separated by a space for the passage of trailing yarn, 70 said trip-pins having screw-threaded stems providing for adjustment of the trip-pins in the direction of their length.

5 In a bobbin-stripper machine, the combination with stripper-devices and an inclined bobbin-chute in which a bobbin hangs suspended by its head from opposite guideways as it progresses toward the stripper-devices, of a bobbin-trip which is encountered by the tip of the descending bobbin, and means providing for shift of the said trip positions at different distances from the said guideways to suit different lengths of bobbins.

10 6. In a bobbin-stripper machine, the combination with stripper-devices and an inclined bobbin-chute in which a bobbin hangs suspended by its head from opposite guideways as it progresses toward the stripper-devices, of a bobbin-trip which is encountered by the tip of the descending bobbin, and supports having at different distances from said guideways holes to receive said trip, the plurality of holes providing for shift of the trip relative to the guideways to suit different lengths of bobbins.

15 7. In a bobbin-stripper machine, the combination with a reciprocating cross-head, bobbin-gripping jaws upon said cross-head, and means for feeding bobbins to said jaws, of stripping blades adapted to engage a residual mass of filling upon said bobbin, and other stripping blades adapted to engage said bobbin between the filling and the shoulder of the head of the bobbin.

20 8. In a bobbin-stripper machine, the combination with a reciprocating cross-head, bobbin-gripping jaws upon said cross-head, stripping members, and means for feeding bobbins to the latter, of a shutter pivotally mounted to permit it to be swung into position opposite the said stripping members, and actuating connections for said shutter having provisions for lost-motion and play to permit the shutter to be arrested by a misplaced bobbin 110 without injurious results.

25 9. In a bobbin-stripper machine, the combination with a reciprocating cross-head, bobbin-gripping jaws upon said cross-head, stripping members, and means for feeding bobbins to the latter, of a shutter pivotally mounted to permit it to be swung into position in line with the stripper-members, said shutter having an arm with a slot therein, a rockshaft having an arm, and a pull-rod connected with the latter arm and having an engaging member working in said slot.

30 10. In a bobbin-stripper machine, the combination with a stripper-blade, a lever with which said blade is connected, a swinging

- actuating arm, and means for yieldingly transmitting movement from said actuating arm to said lever comprising a stud or pin engaged with one thereof and passing through a hole in the other, and a spring confined between one of said parts and a stop upon the stud or pin, whereby when the arm is moved it acts through the spring to transmit power to the lever, of means for adjusting the stroke of the stripper-blade comprising an adjustment stud connected with one of said parts and engaging with the other to effect angular shift of the lever with respect to the arm.
11. In a bobbin-stripper machine, the combination with a reciprocating cross-head, stripping members, and means for feeding bobbins to the stripping members, of gripping-jaws pivotally mounted upon said cross-head, a member also pivotally mounted upon the cross-head, having cam-slots, and cam-followers upon the said gripping-jaws working in said cam-slots, to force said gripping jaws open or shut as said member is swung in one direction or the other about its pivot.

12. In a bobbin-stripper machine, the combination with a reciprocating cross-head, bobbin gripping-jaws carried thereby, a gripper-actuating cam carried by said cross-head, a latch for locking said cam with the grippers open, and a spring for actuating said cam to close the grippers upon a bobbin when the cam is freed through disengagement of the latch, of a drum upon which the coil of said spring is mounted and with which one end of the spring is engaged, and means for effecting angular adjustment of the said drum to create the required degree of tension in the spring.

13. In a bobbin-stripper machine, the combination with stripping members, means for feeding bobbins to the stripping members, and a reciprocating cross-head, of gripping-jaws mounted upon said cross-head, a gripper-actuating cam carried by said cross-head, and provisions for rendering the gripper-jaws individually adjustable transversely to modify the positions taken by the acting ends of the gripper-jaws when closed together by the action of the said cam.

14. In a bobbin-stripper machine, the combination with stripping members, means for feeding bobbins to the stripping members, and a reciprocating cross-head, of gripping-jaws mounted upon said cross-head, a member pivotally mounted upon said cross-head having cam-slots, cam-followers carried by the gripping-jaws working in said cam-slots to actuate the said jaws upon rotation of said member, a spring tending to rotate said member in a direction to close the jaws, and means to rotate said member reversely to open the jaws, the said cam-followers having eccentric mountings upon the said gripping-jaws

to enable them through angular adjustment to modify the positions taken by the acting ends of the gripping-jaws as they are closed together.

15. In a bobbin-stripper machine, the combination with a reciprocating cross-head, bobbin gripping-jaws upon said cross-head, and means for feeding bobbins to said jaws, broad-faced stripper-blades adapted to engage exteriorly a residual mass of filling upon said bobbin, and chisel-ended stripping blades adapted to engage the bobbin between the filling and the shoulder of the head of the bobbin.

16. In a bobbin-stripper machine, the combination with stripper-devices, and a bobbin-way in which a bobbin hangs suspended by its head between opposite cheeks as it progresses toward the stripper-devices, of a pair of bobbin-trip-pins in connection with said bobbin-way, with the proximate ends of the said pins separated by a space for the passage of trailing yarn.

17. In a bobbin-stripper machine, the combination with a reciprocating head having means to actuate a bobbin endwise as the head moves, and means for presenting a bobbin in position to be actuated thereby, of stripping blades adapted to engage exteriorly a residual mass of filling upon the said bobbin, and other stripping blades adapted to engage said bobbins between the filling and the shoulder of the head of the bobbin.

18. In a bobbin-stripper machine comprising stripping means, a reciprocating cross-head, and bobbin-head-gripping jaws mounted upon said cross-head, the combination with such elements of a member mounted upon said cross-head and movable relative thereto for opening and closing the jaws, said member and said jaws respectively having cam-slots and followers occupying said cam-slots, means for moving said member in one direction to force the jaws open, a latch which engages with such member to lock it with the jaws open, means for causing disengagement of the latch to unlock the said member, and a spring by which when the unlocking takes place such member is actuated to close the jaws upon a bobbin which is to be moved past the stripping means.

19. In a bobbin-stripper machine, the combination with stripper-blades, and a reciprocating bobbin-pulling device, of a wiper or clearer by which turns of yarn remaining on a bobbin-barrel after being pulled past the said stripper-blades are wiped off, spring-actuated to carry it toward the path of the bobbin, and displaced by the bobbin-pulling device, in the stroke of the latter to engage with the bobbin, from the said path so as to provide clearance for the pulling-device and bobbin-head.

20. In a bobbin-stripper machine, the combination with stripper-blades, and a recip-

roating bobbin-pulling device, of wipers or clearers by which turns of yarn remaining on a bobbin-barrel after being pulled past the said stripper-blades are wiped off, spring-actuated to impel their wiping portions toward the path of a bobbin as the latter is drawn past the stripper-blades, and spread apart by the bobbin-pulling device as the latter makes its stroke toward the stripper-blades.
